SULZER FRERES SOCIETE ANONYME, OF WINTERTHUR, SWITZERLAND

HIGH PRESSURE RECIPROCATING PISTON COMPRESSOR

Original application filed February 3, 1928, Serial No. 251,714, and in Switzerland June 8, 1927.

Divided and this application filed January 30, 1930. Serial No. 424,555.

This invention relates to high pressure piston or reciprocating compressors or the like of the kind in which the working pistons of the compressor or their intermediate pistons are actuated by primary or driving pistons which are preferably exposed on both faces to the action of a column of liquid.

The output of such compressors has hitherto been limited by the dimensions of the last stage and not by the power of the driving apparatus, the dimensions of the last stage being themselves limited by the question of packing the working piston and stuffing boxes. In fact, as regards the latter there is a definite diameter, which if exceeded, cannot be efficiently packed with the means at present available.

The invention has for its object to provide an improved construction of such compressors in which these disadvantages are obviated and the output increased while simplifying the driving mechanism.

According to the present invention at least two intermediate pistons respectively actuate the individual working pistons of two or more compressor cylinders arranged in parallel for the purpose of increasing the output of the compressor while simplifying the driving mechanism. By the term "arranged in parallel", as used above and throughout the remainder of the description, is intended to be meant the arrangement of the cylinders whereby they operate in the same stage.

The liquid columns which act on the intermediate pistons of these cylinders are preferably all actuated by one and the same primary piston. The cylinders may be arranged in pairs and the intermediate pistons of each pair may be connected by a column of liquid disposed in the same plane as that in which is disposed the column of liquid connecting one of the pairs of intermediate pistons and the corresponding primary piston. Alternatively, the liquid column between the intermediate pistons of each pair may be disposed in a plane transverse to the plane in which is disposed the liquid column between one of the pairs of intermediate pistons and the corresponding primary piston.

A few constructional examples of the in-

vention are illustrated diagrammatically by way of example in the accompanying drawings, in which

Figure 1 is a sectional view of two stages, for example the two uppermost stages, of one form of piston compressor according to the invention,

Figure 2 is a plan view of a modification of the arrangement of Figure 1,

Figure 3 is a sectional view on the line III-III of Figure 2.

In the construction illustrated in Figure 1 the movement of the liquid columns within the cylinders 8, 9 and 10 is effected by double-acting primary pistons 5, 6 and 7 mounted on a piston rod 4 which is connected to the crank 1 of the driving machine (not shown) through a cross-head 3 and connecting rod 2. In the cylinders 13, 14, 15 and 16 are provided the intermediate pistons 19, 20, 21 and 22, mechanically connected to the compressor pistons 23, 24, 25 and 26 respectively, which act on the medium to be compressed in the cylinders 27, 28, 29 and 30 of the second last stage. In the cylinders 11 and 12 of the last stage are mounted intermediate pistons 17 and 18 mechanically connected to the compressor pistons 31 and 32 of the compressor cylinders 33 and 34. Between the primary pistons 5, 6 and 7 and one face of each of the intermediate pistons 17, 18, 19, 20, 21 and 22 are provided liquid columns 35, 36, 37, 38, 39 and 40 respectively, and between the adjacent intermediate pistons 17 and 18, 19 and 20, and 21 and 22 are respectively provided liquid columns 41, 42 and 43. To the suction pipe 44 for the cylinders 27, 28, 29 and 30 of the second last stage are connected the suction valves 45, 46, 47 and 48, the delivery valves 49 and 50 for the cylinders 30 and 29 of this stage being connected to the suction pipe 51 and the suction valve 52 for the cylinder 34 of the last stage of the compressor, while the delivery valves 53 and 54 for the cylinders 28 and 27 are connected to the suction pipe 55 and the suction valve 56 for the cylinder 33 of the last stage. The delivery pipe 59 for the last stage leads from the delivery valves 57 and 58 for the cylinders 34 and 33 to the

point of consumption of the compressed gas. The liquid columns between the adjacent intermediate pistons are arranged in the same plane as the liquid columns between one intermediate piston and the corresponding primary piston.

The intermediate pistons 19, 20, 21 and 22, actuated by the primary pistons 6 and 7, cause the compressor pistons 23, 24, 25 and 26 to act on the medium within the cylinders 27, 28, 29 and 30 respectively, which are arranged in parallel, while the intermediate pistons 17 and 18 actuated by the primary piston 5 cause the compressor pistons 31 and 32 to act on the medium within the cylinders 33 and 34 respectively, which are also arranged in parallel.

The construction shown in Figures 2 and 3 differs from that shown in Figure 1 in that the liquid columns between adjacent intermediate pistons are disposed in a plane transverse to the plane of the liquid column between one of the pairs of intermediate pistons and the corresponding primary piston. In this arrangement the axes of the liquid columns 78 and 79 between the intermediate pistons 62 and 63 and between the intermediate pistons 66 and 67 are disposed perpendicularly to the axes of the primary pistons 60 and 61. The cylinders 70 and 71 accordingly are arranged in parallel, as are also the cylinders 72 and 73.

With this construction, the primary pistons 60 and 61 act on the pairs of intermediate pistons 62-63 and 66-67 of the cylinders 64-65 and 68-69. The intermediate pistons 62-63, actuated through the liquid columns 74 and 75 by the primary piston 60 and connected by the liquid column 78, actuate the compressor pistons 82 and 83 of the cylinders 70 and 71, which are arranged in parallel. Similarly, the intermediate pistons 66-67, actuated through the liquid columns 76 and 77 by the primary piston 61 and connected by the liquid column 79, act in a similar manner on the compressor pistons of the cylinders 68 and 69, which also are arranged in parallel. The supply to the suction valves is effected by the pipe 80 while the discharge takes place from the delivery valves through the pipe 81.

The invention enables the output of the known type of compressor to be doubled, in spite of the fact that the driving mechanism is considerably simplified and the plunger diameter remains the same. The diameter of the stuffing boxes, shown only diagrammatically, does not become excessive and the reduction in the dimensions reduces the extent to which the packing heats up, so that frictional heat can be more readily dissipated. In addition, expansion due to heat is reduced and the play between the piston and the packing elements is therefore less.

65 This application is a division of U. S. ap-

plication, Serial No. 251,714 filed February 3, 1928 and issued as Patent No. 1,767,404, June 24, 1930.

I claim:

1. In a high pressure reciprocating compressor, the combination with a positively actuated primary piston, of a plurality of intermediate pistons, a plurality of compressor pistons arranged in parallel and each actuated by one of said intermediate pistons, an oscillating column of liquid between one side of said primary piston and one of said intermediate pistons, an oscillating column of liquid between the other side of said primary piston and another of said intermediate pistons, and an oscillating column of liquid between said intermediate pistons, said last named column being disposed in a plane transverse to that in which are disposed said first named columns. 70

2. In a high pressure reciprocating compressor, the combination with a plurality of positively actuated primary pistons, of a plurality of intermediate pistons, a plurality of compressor pistons arranged in parallel and each actuated by one of said intermediate pistons, an oscillating column of liquid between one side of each of said primary pistons and one of said intermediate pistons, an oscillating column of liquid between the other side of each of said primary pistons and another of said intermediate pistons, and an oscillating column of liquid between the first and last named of said intermediate pistons, said last named column being disposed in a plane transverse to that in which are disposed said first named columns. 80

3. In a high pressure reciprocating compressor, the combination with a horizontally disposed positively actuated primary piston, of a plurality of vertically disposed intermediate pistons, a plurality of compressor pistons arranged in parallel pairs and each actuated by one of said intermediate pistons, an oscillating column of liquid between one side of said primary piston and one of said intermediate pistons, an oscillating column of liquid between the other side of said primary piston and another of said intermediate pistons, and an oscillating column of liquid between said intermediate pistons, said last named column being disposed in a plane transverse to that in which are disposed said first named columns. 100

4. In a high pressure reciprocating compressor, the combination with a plurality of horizontally disposed positively actuated primary pistons, of a plurality of vertically disposed intermediate pistons, a plurality of compressor pistons arranged in parallel pairs and each actuated by one of said intermediate pistons, an oscillating column of liquid between one side of each of said primary pistons and one of said intermediate pistons, an oscillating column of liquid between the other side of each of said primary pistons and another of said intermediate pistons, and an oscillating column of liquid between said intermediate pistons, said last named column being disposed in a plane transverse to that in which are disposed said first named columns. 110

side of each of said primary pistons and another of said intermediate pistons, and an oscillating column of liquid between the first and last named of said intermediate pistons,
5 said last named column being disposed in a plane transverse to that in which are disposed said first named columns.

In testimony whereof I affix my signature.
CHARLES SCHAER.
